US00D532960S

(12) **United States Design Patent** (10) **Patent No.:** **US D532,960 S**
Pellerin (45) **Date of Patent:** **** Dec. 5, 2006**

- (54) **CLEAT**
(75) Inventor: **Daniel Pellerin**, Varennes (CA)
(73) Assignee: **Penguin Brands, Inc.**, Sharon Hill, PA (US)
(**) Term: **14 Years**
(21) Appl. No.: **29/218,752**
(22) Filed: **Dec. 7, 2004**

(57) **CLAIM**

I claim the ornamental design for a cleat, as shown and described.

DESCRIPTION

FIG. 1 is a right front perspective view of a cleat showing my new design, with the cleat being upside down from its position when in use.

FIG. 2 is a right side elevational view thereof, the left side being a mirror image.

FIG. 3 is a front elevational view thereof.

FIG. 4 is a rear elevational view thereof.

FIG. 5 is a top plan view thereof; and,

FIG. 6 is a bottom plan view thereof.
